VALVE MECHANISM FOR DRAFT-REGULATORS.

1,031,458.

Specification of Letters Patent.

Patented July 2, 1912.

Application filed July 30, 1910. Serial No. 574,687.

To all whom it may concern:

Be it known that I, JOHN MILTON, a citizen of the United States, residing at Washington, in the District of Columbia, have invented a new and useful Improvement 5 in Valve Mechanism for Draft-Regulators, of which the following is a specification.

This invention relates to an improved 10 construction of draft regulator which forms the subject matter of Patents #590,846, September 28, 1897, #631,528, August 22, 1899, #661,066, November 6, 1900 and #776,608, December 6, 1904, granted to me 15 for draft regulators, particularly adapted for use in connection with locomotives. In all of these draft regulating devices an air trap is arranged at the forward end of the locomotive for taking air into the smoke 20 box of said locomotive, whenever the fire box doors are opened and also during excessive exhausts: the sole purpose of said air trap being the introduction of air into the smoke box for the purpose of preventing 25 the disastrous effects or consequences, recited in detail in the patents hereinbefore referred to. In the first two patents before mentioned a purely mechanical connection is had in each instance between the fire box 30 door and the air trap for the purpose of operating the valve of said air trap in unison with said fire box door, while in the other patents referred to, pneumatically operated means are employed to control the 35 valve of the air trap.

Another object of the invention is to provide for the regulation of tension or pressure upon the air inlet valve whereby the rate of movement of said valve can be regulated. 40

This present invention as before stated, relates to this class of draft regulators and more particularly to an improved construction of pneumatic valve mechanism for controlling 45 the air trap valve in connection with the fire box door, and this invention has for its object to provide a valve mechanism which will absolutely prevent the leakage of air and thereby secure the essential economy in its use in the manipulation of the device. 50

Another object of the invention is to pro-

vide a valve mechanism in which all dirt, grit, and other foreign matter will be arrested at the receiving point and prevented 55 from coming in contact with the working parts of the mechanism, whereby a much more effective and durable device is provided.

Another object of the invention is to provide 60 a valve mechanism having an inlet and an exhaust valve, both of which can be closed simultaneously but only one at a time opened thereby preventing a waste of air and also insuring the proper action of 65 all of the parts operatively connected with said valve mechanism.

A still further object of the invention is to provide a valve mechanism in which the tendency to gum or stick is entirely obvi- 70 ated.

Another object of the invention is to provide 75 an adjustable compensating thrust or connecting rod whereby the operation of the valves can be effected by means of a crank on top of the fire door pintle and a still further object is to provide for the quick and easy cleaning of the entire mechanism of all foreign matter which may accumulate therein. 80

With these various objects in view, I have after numerous tests and experiments provided a valve mechanism which thoroughly carries out all of the objects referred to and consists essentially of a casing having a 85 chamber provided with inlet and exhaust ports, said inlet and exhaust ports being controlled by means of valves which have a common operating means, which operating means is operatively connected with the fire 90 box doors so that the said mechanism will be automatically operated upon the opening and closing of said doors.

The invention consists in various details of construction, and also in certain novel- 95 ties of combination and arrangement hereinafter fully described and pointed out in the claims.

The details of the present invention and mode of operation of the various parts are 100 clearly set forth in the following description taken in connection with the accompanying drawings, illustrating the preferred form of embodiment, it being under-

stood of course that various changes or modifications can be made without departing from the broad principle of the invention.

In the drawings forming a part of this specification: Figure 1 is a view showing the valve mechanism arranged upon the boiler head over the fire box doors and showing the connection between the pintles of said doors and the valve mechanism: Fig. 2 is a top view of the same, certain parts being broken away to more clearly illustrate certain features: Fig. 3 is a vertical sectional view of the valve mechanism: Fig. 4 is a sectional view of the connecting or thrust rod, and, Fig. 5 is a sectional view of the piston for operating the valve or door of the air trap. Fig. 6 is a side elevation of a locomotive, showing the application of my invention. Fig. 7 is a front elevation of the same. Fig. 8 is a rear elevation.

In carrying out my invention, I employ a valve casing A, which is supported upon the head or face of the boiler in any suitable manner, said valve casing being arranged above the fire box doors, and with reference to its operating connection. Leading into this valve casing A is the air inlet pipe A' which carries the air under pressure from any suitable source into the casing, and a second pipe A² is also connected to this casing and through which air is carried to the forward end of the locomotive for the purpose of operating the piston hereinafter described, which piston operates the valve or door in the air trap at the forward end of the locomotive.

The main object of my invention is to provide for the influx of air into the smoke box whenever the fire box doors are opened and inasmuch as the valve mechanism which forms the subject matter of this application is for the purpose of controlling the air under pressure for actuating said valve at the forward end it is obvious that there must be a connection between the fire box doors and the valve mechanism and this I accomplish by providing pintles B which are keyed or otherwise fixed to the fire box door hinges, each pintle being in turn provided with a disk B' at its upper end and each disk is provided with a crank pin B² and it will be noted that where there are two fire doors one crank pin B² is arranged upon one side of the longitudinal line connecting the disks, while the other crank pin occupies a position upon the opposite side of said line. Connecting these disks B² is a horizontal shiftable bar B³ having slots B⁴ produced adjacent its ends and in which the crank pins B² work and it is obvious that from the relative arrangement of the slots, pins and disks carried by the pintles that as the said pintles are rotated in one direction, the bar will be caused to shift in one direc-

tion and upon the return movement of the pintles, said bar will shift in the reverse direction as most clearly indicated on the drawing by means of arrows. Where there is but one fire door, there is a direct connection through the connecting rod between the pintle and valve lever. It will be understood that this shiftable bar is for the purpose of communicating motion to the valve mechanism whenever the fire box doors are opened and closed and this motion I communicate to the operating lever of the valve mechanism hereinafter referred to, by means of a connecting rod C, which is attached to the shiftable bar B³ at one end while at the opposite end the connecting rod is attached to the valve operating lever. This connecting rod C is in the nature of a compensating rod as the movement of the valve operating lever is not coextensive with the movement of the shiftable bar B³ and in order to compensate for this difference in movement, I preferably make the connecting rod C in two sections C' and C², which sections enter a sleeve C³ and the section C' is provided with a head C⁴ against which bears a spring C⁵ and between this head and the opposite end of the sleeve is another spring C⁶, the purpose of said springs being to normally hold the sections of the rod extended to their proper positions. The section C² of the rod is threaded into the end of the sleeve so that a fine adjustment can be had for the said rod in connecting the same with the valve operating lever. It will thus be seen that I provide not only an adjustable rod but also a spring actuated compensating mechanism contained within said rod by means of which the differential movements between the shifting bar and valves is compensated for. As before stated this connecting rod is connected at one end to the valve operating lever and I will now proceed to describe the valve mechanism in detail.

The valve casing has been described as attached to the head or boiler or out at a point above the fire box doors and this air valve casing is constructed with two vertical bores or chambers D and E respectively and also with two horizontal bores or passages F and G, respectively and this valve casing also has a vertical lever passage H, all of said passages, chambers or bores being arranged in the same vertical plane. The chamber D is bored from the bottom upwardly and extends nearly through the casing and the chamber E is bored entirely through the casing as most clearly shown and these chambers D and E are closed at their lower ends by means of screw plugs D' and E' respectively. The air inlet pipe A' enters the chamber D about midway its height and the air delivery pipe A² extends from the chamber E at its upper end and between the chambers D and E is a port I, controlled by

means of a lever K, the head of which is ground to fit accurately the seat of the port I and it will be noted that this port I is out of horizontal alinement with the air inlet 5 pipe and is preferably arranged above said inlet pipe although it could be arranged below if so desired.

The chamber D I prefer to designate as the receiving chamber and the chamber E 10 the distributing chamber and inasmuch as the port connecting these chambers is out of horizontal alinement with the inlet pipe, it is obvious that any dust, or dirt or other foreign matter carried into the receiving 15 chamber would be caught or intercepted and will collect in the bottom thereof and will not pass out through the port I. The accumulated dust or dirt can be quickly and easily removed whenever desired by opening 20 the plug D' at the bottom of the chamber D.

A port L is arranged adjacent the upper end of the chamber E and communicates with the bore or passage G in which is located the exhaust valve M, the end of which is ground 25 to accurately fit the seat of the port L and it will also be noted that the end of the valve is reduced in order to permit the exhaust valve to pass freely to the outlet opening L' produced in the side of the casing and communicating 30 with the exhaust port L or rather communicating with the passage G adjacent the said port L. The inlet valve K and the exhaust valve M move horizontally back and forth and the inlet valve K 35 is normally held closed by means of a spring K' exerting the pressure upon the rear end thereof, the tension of said spring being regulated by means of a screw plug K² screwed in the end of the valve casing 40 and bearing upon the coil spring K' which in turn, as before stated, exerts its pressure upon the rear end of the inlet valve K for the purpose of maintaining it in its closed position. The inlet and exhaust valves are 45 both operated by means of a single lever N, said lever being bifurcated at its upper end and pivotally connected with the exhaust valve as shown and intermediate its end this lever is pivotally connected with the inlet 50 valve K, the lever being slotted or bifurcated and the valves are reduced as shown for the purpose of making the ends connect. The lower end of this lever N is connected to the section C' of the connecting rod C so that as 55 the fire box doors are swung open the bar B³ is shifted and this in turn communicates motion to the connecting rod which exerts either a push or pull upon the lever N according to the position of the valve. The 60 inlet valve is normally closed and the initial movement of the operating lever N serves to close the exhaust valve, said lever turning upon a pivot N' as a fulcrum and then the continued movement of the lever N shifts the 65 fulcrum from the pivot N' to the pivot N²

and the fulcrum being shifted and the exhaust valve closed the inlet valve is forced back or opened and the air will immediately enter the receiving chamber pass through the inlet port into the distributing chamber 70 and out through the outlet pipe A² to the valve controlling piston mechanism at the forward end of the locomotive. All of these operations occur simultaneously with the opening of the fire box doors and are brought about by the operation of said doors. When the doors are closed the reverse movements take place so far as the actuating mechanisms are concerned and consequently the lever end returns to its normal position and 75 the spring immediately causes the inlet valve to be seated and the exhaust valve opens the exhaust port and consequently the air passes out through the port L and outlet opening L' into the air.

The hereafter described valve mechanism is the result of numerous experiments and tests already made with the object of insuring simplicity of parts and efficiency of operation and it is obvious that the mechanism 80 consists of very few parts all of which can be quickly and easily assembled and it is also obvious that owing to the quick and positive manner of operating the inlet and exhaust valves there will be no leakage of 85 air and it is also clear that all dust, dirt or other foreign matter which would ordinarily pass to the mechanism and tend to clog the same, are caught or entrapped in the receiving chamber.

After the air passes into the outlet pipe A², it is carried forward to the forward end of the locomotive and introduced into the bottom of a cylinder O in which works a piston P, the rod P' of which is connected 90 with the valve of the air trap arranged in the smoke box door and it will be noted that this piston rod is of a peculiar nature consisting of a stub P² rigidly attached to the piston proper and working in the recess 95 end of the rod P'. A coil spring P³ surrounding the rod and held between the piston and the upper end of the cylinder O, the purpose of said construction being to permit the valve of the air trap to automatically 100 open whenever an excessive exhaust in the smoke box occurs, without disturbing the valve operating mechanism which is attached to the boiler head and operated from the fire box doors. When the fire box doors 105 are closed, the parts assume their normal positions as shown in Fig. 3, and the compressed air contained within the cylinder O and connecting pipe A² is permitted to exhaust through the exhaust opening L'. 110

To illustrate the application of my invention, I have shown the same applied to a locomotive 20, as indicated in Figs. 6, 7, and 8. The air pipe A², is shown as connected to the cylinder O, and the latter is 115 120 125 130

connected by a link 21, with a gate 22, pivoted in a short flue 23, arranged in the front of the boiler.

From the above description taken in connection with the accompanying drawings, it will be seen that I provide a simple and efficient construction of air valve mechanism by means of which all of the objects hereinbefore referred to are accomplished.

10 Having thus described my invention, what I claim as new and desire to secure by Letters Patent, is:

1. In combination, a valve comprising a casing provided with an air inlet chamber and an air outlet chamber, said casing having a passage communicating with said air inlet and outlet chambers and a port leading from the air outlet chamber, an inlet valve mounted in the casing and straddling the air inlet chamber to control the passage, a spring for normally closing said inlet valve, an exhaust valve mounted in the casing to control the exhaust port, a lever pivoted to the inlet valve and extending beyond the casing in one direction and to the exhaust port in the opposite direction, a pivotal connection between the exhaust port and the lever, a boiler provided with a door at one end and an opening at the opposite end, a connection between the door and the lever, whereby when said door is opened the lever will be operated to open the passage and close the exhaust port, a gate coöperating with the opening in the boiler, a valve pivoted to the gate, means for normally seating the valve and closing the gate, a pipe communicating with the valve and the air outlet opening in the casing to permit air to operate the valve and open the gate, when the door of the boiler is opened, and means coöperating with the valve to permit the gate to open independently of the door by excessive draft in the boiler.

2. In combination, a boiler provided with a fuel door and an opening, a casing adjacent the fuel door, said casing having an inlet chamber and outlet chamber connected by a passage and an exhaust port communicating with the outlet chamber, a valve for closing the passage, a valve for controlling the exhaust port, a lever for operating the valves, said lever when moved in one direction first operating the exhaust valve to close the exhaust port and subsequently operating the inlet valve to open the passage between the inlet and outlet chambers, means coöperating with the lever to first cause it when moved in the opposite direction to operate the inlet valve to close the inlet port and upon further movement operate the exhaust valve to open the exhaust port, a connection between the door and the lever to operate the latter when the door is moved, a gate coöperating with the opening in the boiler, a valve connected to the gate,

a pipe connecting the outlet chamber and the valve, said valve including means for permitting of the gate being opened by excessive exhaust in the boiler and independent of the opening of the door.

3. A valve mechanism comprising a casing having air inlet and outlet pipes connected therewith, said casing having two vertical bores and two horizontal bores all in the same vertical plane, said vertical bores providing receiving and distributing chambers and the horizontal bores providing valve passages, one of said chambers being provided with an exhaust port, the casing having a passage between the inlet and outlet chamber, an inlet in one of the valve passages to control the passage between the inlet and outlet chambers, an exhaust valve in the other valve passage to control the exhaust port, and an operating lever connected at one end with the exhaust valve and also connected at its ends with the inlet valve.

4. A valve mechanism comprising a casing having air inlet and outlet pipes connected therewith, said casing having two vertical bores and two horizontal bores all in the same vertical plane, said vertical bores providing receiving and distributing chambers, and the horizontal bores providing valve passages, one of said chambers being provided with an exhaust port, the casing having a passage between the inlet and outlet chambers, an inlet in one of the valve passages to control the passage between the inlet and outlet chambers, an exhaust valve in the other valve passage to control the exhaust port, an operating lever connected at one end with the exhaust valve and also connected intermediate its ends with the inlet valve, and means for normally holding the inlet valve closed.

5. A valve mechanism comprising a casing having inlet and outlet pipes connected therewith, said casing having two vertical bores and two horizontal bores and a vertical lever recess all in the same vertical plane, said vertical bores providing receiving and distributing chambers and having plugs in their lower ends, the horizontal bores providing valve passages, one of said chambers being provided with inlet and exhaust ports, valves arranged in the passages for controlling the inlet and exhaust ports, means for normally holding the inlet valves closed, and a lever located in the recess and pivotally connected at its ends to the exhaust valve and pivotally connected intermediate its ends to the inlet valve for the purpose specified.

6. In combination, a boiler provided at its front end with a draft inlet, fuel doors having pintles at the rear end of said boiler, a valve casing adjacent the doors, said casing having a chamber into which leads a pipe, a

second chamber formed in the casing and with which communicates an outlet pipe, there being a port formed between the two chambers, a valve in the casing for controlling said port, means for automatically closing said valve, the casing having an exhaust port communicating with the second mentioned chamber, an exhaust valve in the casing to coöperate with the exhaust port, a lever pivoted to the exhaust port and the first mentioned valve and extending beyond the casing, a rod connected to the pintles of the fuel doors, a sectional connection between the lever and the connecting rod comprising a sleeve on one section, a headed rod on the other section, springs interposed between the head rod and the ends of the sleeve, a gate for the draft opening, and a valve in the outlet pipe for operating the gate when the fuel doors are opened.

7. In combination, a boiler provided with a draft opening at its front end, a gate co-operating with said draft opening, a cylinder, a piston in the cylinder, a connection between the piston and said gate, fuel doors having pintles on the boiler, a longitudinal shiftable bar connecting the pintles of said doors, a valve casing adjacent the fuel doors, said casing having inlet and exhaust ports, valves controlling the inlet and exhaust ports, a pipe communicating with the exhaust port and the gate valve, a lever connected with said inlet and exhaust valves and extending from the casing, a connecting rod pivoted to the shiftable bar and the lever whereby when the doors are opened the valves will be operated and the piston will be moved and the gate opened.

8. In combination, a boiler formed at its front end with a draft opening, a gate therefor, a cylinder, a piston in the cylinder, a connection between the piston and the gate, hinged fuel doors on the boiler, disks on the pintles of the doors, each disk having a crank pin, a valve casing having an inlet and an outlet chamber and inlet and exhaust ports, a pipe communicating with the outlet chamber and the cylinder, a valve con-

trolling the inlet port, an exhaust valve for controlling the exhaust port, a lever pivotally connected to the inlet and exhaust valves, a bar having slots with which the crank pins engage, and a connecting rod connected at one end to the bar and at its opposite end to the lever.

9. In combination, a boiler formed at one end with a draft opening, a gate therefor, a cylinder, a piston in the cylinder, a connection between the piston and the gate, movable fuel doors on the boiler, a valve casing having an inlet and an outlet chamber and inlet and exhaust ports, a pipe communicating with the outlet chamber and the cylinder, a valve controlling the inlet port, an exhaust valve for controlling the exhaust port, a lever pivotally connected to the inlet and exhaust valves, and a connection between the lever and the doors whereby when the door is opened the valves will be operated to admit pressure to the outlet chamber and operate the piston.

10. In combination, a boiler formed at one end with a draft opening, a gate therefor, a cylinder, a piston in the cylinder, a connection between the piston and the gate, means in the cylinder for permitting the gate to open when excessive draft occurs in the boiler, movable fuel doors on the boiler, a valve casing having an inlet and an outlet chamber and inlet and exhaust ports, a pipe communicating with outlet chamber and the cylinder, a valve controlling the inlet port, an exhaust valve for controlling the exhaust port, a lever pivotally connected to the inlet and exhaust valves, and a connection between the lever and the doors, whereby when the door is opened the valves will be operated to admit pressure to the outlet chamber and operate the piston, said operation of the piston being independent of the operation of the gate under excessive draft.

JOHN MILTON.
